CLAIM

The ornamental design for a cosmetic bag, as shown and described.

DESCRIPTION

FIG. 1 is a front view of the present cosmetic bag;

FIG. 2 is a rear view of the cosmetic bag;

FIG. 3 is a top view of the cosmetic bag;

FIG. 4 is a bottom view of the cosmetic bag;

FIG. 5 is a left side view of the cosmetic bag;

FIG. 6 is a right side view of the cosmetic bag; and,

FIG. 7 is a fragmentary cross-section view of the cosmetic bag taken along line 7—7 of FIG. 3.

The broken lines on the side pockets represent stitching and are part of the claimed design.
